UNITED STATES PATENT OFFICE.

WILLIAM E. GOCHENOUR, OF PORTAGE, WISCONSIN.

AUTOMATIC TELLURIAN.

Application filed March 5, 1923. Serial No. 623,007.

To all whom it may concern:

Be it known that I, WILLIAM E. GOCHENOUR, a citizen of the United States, and resident of Portage, in the county of 5 Columbia and State of Wisconsin, have invented certain new and useful Improvements in Automatic Tellurians; and I do hereby declare that the following is a full, clear, and exact description thereof.

10 This invention relates to automatic tellurians.

One of the objects of this invention is to provide a tellurian which gives the correct motion of the several parts of the apparatus 15 and illustrates the varying seasons, night and day, the different phases of the moon, and other similar phenomena.

Further objects are to provide a tellurian which is electrically driven in a continuous 20 and convenient manner, to thereby allow the demonstrator to devote his entire attention to illustrating the various features which he desires to emphasize; and to provide a tellurian which is electrically lighted 25 in a manner to simulate the substantially parallel rays of the sun.

Further objects are to provide a tellurian which is so organized that portions thereof 30 may be readily disconnected from the main drive so that the demonstrator may rapidly run through the seasons, for instance, or give other demonstrations without waiting until the parts have been automatically moved to the desired position; to provide a tellurian 35 which may be readily separated to facilitate packing and shipping without, however, in any way damaging the apparatus; and to provide a tellurian in which the electrical connections are automatically established 40 when the parts are again slipped into position.

An embodiment of the invention is shown in the accompanying drawings, in which:

Figure 1 is a side elevation of the device, 45 with parts in sections to more clearly illustrate the mechanism.

Figure 2 is a vertical section view on line 2—2 of Figure 1.

Figure 3 is a detail of the main journal 50 or bearing of the device, such view being partly in section and drawn to an enlarged scale.

Referring more particularly to the drawings, it will be seen that the tellurian 55 comprises a base which may consist of a hollow

member or housing 1, with a removable bottom plate 2, held in position by means of the threaded legs or supports 3. Within this base an electric motor, 4, is mounted upon the base plate 2, as shown in the drawings, 60 and is provided with a worm 5, upon its drive shaft. A U-shaped bracket 6, is secured to the base and furnishes bearings for a transverse shaft 7, upon which are rigidly mounted a worm wheel 8 and a bevel gear 65 9. The bevel gear 9 meshes with a second bevel gear 10, which is carried upon a projectional shaft 11, journaled in the upper portion of the bracket 6; this shaft is provided with a pinion 12, which may be conveniently located upon its upper end and which meshes with a larger gear 13. The gear 13 is rigidly secured in any convenient manner, as by means of a screw 14, to a sleeve 15, revolvably mounted in a larger 70 sleeve 16. This larger sleeve 16, is rigidly supported from the base or housing 1, and locked in position by means of a screw or other suitable fastening 17, as may be seen from Figure 3. The upper end of the sleeve 80 15 is provided with an outwardly extending flange 18, which rests upon the upper end of the sleeve 16, which sleeve 16 furnishes, therefore, a support for the sleeve 15 and the gear 13. A pair of bevel gears, 19 and 20, of different diameters, are rigidly attached to the stationary sleeve 16,—the smaller of such gears, 20 being mounted above the larger gear, as illustrated in the drawings, for a purpose hereinafter to be 85 described.

A horizontal beam 21, is rigidly secured to a sleeve 22, in any convenient manner, as by means of a nut 23, threaded upon the upper end of such sleeve and clamping the 90 beam against a lower collar 24. See Figure 3. The sleeve 22 is mounted within the sleeve 15 and is loosely splined thereto, as indicated at 25. The lower end of the sleeve 22, carries an electrical contact 25', mounted in a suitable insulating disc which bears against a stationary contact 26, which may be conveniently supported by an insulating member 27, extending from the bracket 6. A suitable lead 28 is connected 100 to the stationary contact 26, and a wire 29 is connected to the movable contact 25', and extends upwardly through the hollow portion of the sleeve 22. This wire extends to an electrical lamp 30—the other terminal 105

of the lamp being connected to the frame of the machine and communicating with a source of electrical energy by way of the lead 31—see Figure 3—connected to some 5 suitable portion of the apparatus. The lamp is conveniently carried by a standard 32, rigidly attached to the shorter arm of the beam 21. A reflector 33, is carried by the standard 32, in any convenient manner 10 and aids in directly projecting the rays in an approximately parallel manner towards the other end of the apparatus.

The longer arm of the beam 21 carries a revolvably mounted frame 34—see Figure 1—15 through which extends a vertical shaft 35. This shaft is provided with a driving gear 36, which meshes with a bevel gear 37, carried by a horizontal shaft 38. The upper end of the shaft 35, is rigidly attached to the frame 34. This lower end, however, is detachably connected to the gear 36. The coupling or joint between the gear 36 and the shaft 35, may be of any desired type, as 20 for example, the slotted collar and pin illustrated at 36'. A second horizontal shaft 39, is mounted above the shaft 38 and is similarly provided with a bevel gear 40, meshing with a bevel gear 41, coaxial with the shaft 35, and free with reference to said 25 shaft. This latter gear is rigidly mounted upon a sleeve 42, which is revolvably carried by the beam 21 and is attached to and carries at its upper end a gear 43. The shafts 38 and 39 are provided at their ends with 30 bevel gears 44 and 45, respectively, such shafts may be conveniently carried within brackets 45', mounted upon the underside of the beam 21. The gears 44 and 45 mesh respectively with the gears 19 and 20, which 35 are rigidly mounted upon the stationary sleeve 16, as previously described.

The revolvble frame 34, rigidly supports a sleeve 46, which projects upwardly therefrom at an angle of $23\frac{1}{2}$ degrees to a vertical line. This sleeve loosely carries a hub 47, which is formed into a gear 48, adjacent its lower end. A sphere 49 is rigidly attached to the hub 48, adjacent its lower portion, and adjacent its upper portion pivots 50 upon the sleeve 46. This sphere is intended to represent the earth and is appropriately provided with a map upon its outer surface. The shaft 35 is rigidly attached to the frame 34. The outer end of the frame carries a shaft 50, which at its lower end is provided with a rigidly attached pinion 51 meshing with a stationary gear 52, secured to the beam 21, as indicated at 53. The upper end of the shaft 50 has rigidly attached thereto 55 a relatively large gear 54, which, through the medium of an idler 55, communicates its motion to a gear 56—such latter gear 56, meshing with the gear 48 and serving therefore to rotate the sphere 49 as the framework 60 34 is slowly moved. If desired, a compass,

57, may be provided upon a projecting arm of the framework 34. The pinion 51 is detachably joined to the shaft 50, in any suitable manner, as by means of the slotted collar 51', so that it may be moved into and 70 out of engagement therewith.

Within the sleeve 46 a relatively small shaft 58 is revolvably mounted and carries at its lower end a gear 59, meshing with the gear 43 previously described. The upper end 75 of the shaft rigidly carries a bevel gear 60, meshing with a bevel gear 61, said latter gear being carried by a shaft mounted within a bracket 62, carried by the sleeve 46. The gear 61 is rigidly attached to the rod 63, which at one end carries a sphere 64, designed to represent the moon, and at its other end a counterweight 65. A counterweight 66 of any desired type may be provided at the outer end of the shorter arm 80 of the beam 21, so as to balance the mechanism carried by such beam. It will be seen that the device consists of a main balanced mechanism pivoted to the main axis of the apparatus and an auxiliary balanced mechanism pivoted to the outer end of the longer arm of the beam 21.

The operation of the apparatus is as follows:—The motor 4 is started and controlled by the snap switch 67, mounted in its base, and slowly rotates the sleeve 15—see Figure 3,—thereby slowly rotating the beam 21. As this beam rotates, motion is communicated to the shafts 38 and 39, which in turn drive the shaft 35 and the sleeve 42. As the sleeve 42 rotates, its gear 43 drives the smaller gear 59, which causes the sphere 64, representing the moon, to travel about the sphere 49. The shaft 35 swings the framework 34 around, and causes the pinion 51 to 100 rotate at a more rapid rate. This motion is multiplied by the gears 54, 55 and 56 and communicated to the pinion 48, which is rigidly attached to the sphere 49, representing the earth, thereby rotating the earth 105 about its axis. At the same time, however, the frame 34 rotates and causes the axis of the earth to assume different angular positions, and consequently causes the orbit of the sphere 64, to vary and to be positioned at different places above and below the plane 110 representing the orbit of the earth about the sun or centering-point of the entire apparatus.

The angular setting of the gear 61 is such that the sphere 64 travels in an orbit, which varies from 5 degrees above to 5 degrees below the orbit of the sphere 49, about the central point of the entire apparatus. While these motions are being executed, the beam 21 is slowly rotating about its pivot point, thereby causing the sphere 49 and its attached parts to travel about the central point of the entire apparatus, simulating the motion of the earth around the sun. 115

The electric lamp, together with its reflec-

tor, furnishes approximately parallel rays, which illuminate substantially half of the sphere 49 and simulate, therefore, the parallel rays of the sun.

5 It will be seen, therefore, that a tellurian has been provided which is driven from an electric motor and electrically illuminated, so that the demonstrator may have free use of his hands and is not required to give 10 any attention whatsoever to the mechanical operation of the apparatus.

If the demonstrator wishes to illustrate the seasons in an extremely rapid manner, he may stop the motor and disengage the 15 gear 36 from the gear 37. He may thereafter rotate the frame 34. This causes the sphere 49 to rotate and similarly causes the sphere 64 to revolve about said first-mentioned sphere. In this manner the various 20 positions of the earth correspond to different seasons and the various positions of the moon may be quickly demonstrated.

If the demonstrator desires, he may disengage the pinion 51 from the gear 52 and also 25 disengage the gear 36 from the gear 37 by sliding such gears upwardly along their respective shafts, as their hubs are slotted and engage pins carried by their respective shafts. Under these conditions he may start 30 the motor and rotate the beam 21. The sphere 49 will therefore remain stationary, together with its axis, with respect to the beam 21, and the demonstrator may therefore illustrate the absolute dependence of 35 the seasons upon the angular setting of the earth's axis with reference to a fixed line in space, for as the apparatus is operated in the manner described, the angular setting of the axis of the sphere 49 will not vary with 40 reference to the beam 21, and consequently seasonal positions will not be simulated.

It is obvious that other of the gears than those described may be detachably associated, so that other combinations may be 45 effected.

When it is desired to ship or pack the tellurian, it is merely necessary to lift the beam 21 upward. The gears 45 and 44 disengage 50 from the gears 19 and 20, and the gear 44 clearing the gear 20. The sleeve 22 lifts freely from the sleeve 15, the loose splined connection permitting this ready detaching. The parts, therefore, will be separated 55 into two main divisions, which may most readily be packed and shipped without subjecting any of the parts to excessive strain due to rough handling.

It is to be noted that the electrical circuit for the lamp is immediately re-established 60 when the parts again reposition, as the contact 25 engages the contact 26 and establishes the circuit for the lamp. It is also to be noted that the loose splined connection insures the correct relative positioning 65 of the parts.

It will be seen that a tellurian has been provided which is electrically driven in a continuous and even manner, thereby allowing the demonstrator to devote his entire attention to the elucidation of the problems which he is illustrating without giving any attention whatsoever to the mechanical operation of the apparatus.

70 It will further be seen that by the provision of the electric lamp, the parallel rays of the sun are substantially duplicated.

If desired, the flat annular surface 68 of the housing center, may be provided with a suitable scale illustrating the different seasons, the months, the day of the month, the 80 signs of the zodiac, or other similar data, and a pointer shown at 69, may be attached to the beam 21 and co-operate with the scale to indicate mechanically the exact phase or position of the parts.

85 Although one specific form of the invention has been described in considerable detail, it is to be understood that the invention may take different forms and such invention, therefore, is to be limited only as defined in the appended claims.

I claim:

1. A tellurian comprising a revolvably mounted frame, an electric motor adapted to rotate such frame, an auxiliary frame carried by said first-mentioned frame and having a sleeve angularly mounted thereon, a sphere mounted upon said sleeve, gearing adapted to rotate said auxiliary frame and said sphere when said first-mentioned frame is rotated, a second independent set of gearing, axially mounted with respect to said auxiliary frame, independent means for operatively connecting said second gearing with a stationary portion of the apparatus, a smaller sphere adapted to be revolved about said main sphere by means of said auxiliary gear, and clutch members adapted to enable the interruption of various operations of the gearing.

90 100 105 110 115 120 125 130

2. A tellurian comprising a base, a shaft projecting therefrom, a stationary electric motor mounted upon said base and operatively coupled to said shaft, a beam carried by said shaft and adapted to be rotated thereby, an electric lamp carried by said beam, an auxiliary frame carried by said beam, a larger and a smaller sphere operatively supported from said auxiliary frame, means for rotating the larger of said spheres about its axis, means for rotating said auxiliary frame, means including a stationary gear, for revolving said smaller sphere about said main sphere, and clutch mechanism adapted to enable the disconnection of certain of said gears whereby the rotation of the main sphere or the rotation of the auxiliary frame may be stopped relatively to the beam.

3. A tellurian comprising a stationary

hollow base, an electric motor mounted therein, a stationary sleeve projecting upwardly from said base, a revoluble shaft carried within said sleeve and operatively coupled to said motor, a beam carried by the projecting end of said shaft and adapted to be rotated thereby in a horizontal plane, a pair of gears carried by said sleeve and fixedly positioned thereon, a pair of horizontally disposed shafts geared to said stationary gears and carried by said beam, a vertical shaft and a vertical sleeve geared to said horizontal shafts, an auxiliary frame carried by said vertical shaft, gearing carried by said auxiliary frame, a stationary gear rigidly attached to said beam, and a pair of spheres of different diameters adapted for relative motion and operatively connected with said gearing carried by said auxiliary frame, one set of gearing being driven from said vertical sleeve and the other set of gearing being driven from said vertical shaft.

4. A tellurian comprising a stationary base having a rigid sleeve projecting therefrom, a revoluble sleeve mounted therein, an electric motor for rotating said revoluble sleeve, a beam adapted for detachable connection with said revoluble sleeve and adapted to be lifted therefrom, gearing carried by said beam, stationary gears carried by said rigid sleeve and co-operating with the gearing carried by said frame, a relatively large sphere carried by said beam and having motion of translation with reference thereto, and operatively coupled to said gearing, and illuminating means carried by said beam, said illuminating means including an electric lamp and a circuit therefor adapted to be opened and closed by the removal and repositioning, respectively, of said beam.

5. A tellurian comprising a stationary base having a rigid sleeve projecting therefrom, a revoluble sleeve mounted therein, an electric motor for rotating said revoluble sleeve, a beam adapted for detachable connection with said revoluble sleeve and adapted to be lifted therefrom, gearing carried by said beam, stationary gears carried by said rigid sleeve and co-operating with the gearing carried by said frame, a relatively large sphere carried by said beam and having motion of translation with reference thereto, and operatively coupled to said gearing, and illuminating means carried by said beam.

5. A tellurian comprising a stationary base having a rigid sleeve projecting therefrom, a revoluble sleeve mounted therein, an electric motor for rotating said revoluble sleeve, a beam adapted for detachable connection with said revoluble sleeve and adapted to be lifted therefrom, gearing carried by said beam, stationary gears carried by said rigid sleeve and co-operating with the gearing carried by said frame, a relatively large sphere carried by said beam and having motion of translation with reference thereto, and operatively coupled to said gearing, said sphere having rotary and rocking motion relative to said beam, a smaller sphere carried by said beam and having motion of translation with reference thereto, and operatively coupled to said gearing, and illuminating means carried by said beam, said illuminating means including an electric lamp and a circuit therefor adapted to be opened and closed by the removal and repositioning, respectively, of said beam.

In testimony that I claim the foregoing I have hereunto set my hand at Milwaukee, in the county of Milwaukee and State of Wisconsin.

WILLIAM E. GOCHENOUR.
